The ornamental design for an automotive head rest cover, as shown and described.

DESCRIPTION

FIG. 1 is a front elevational view of the automotive head rest cover showing my new design;

FIG. 2 is a rear elevational view thereof;

FIG. 3 is a right view thereof;

FIG. 4 is a left view thereof;

FIG. 5 is a top plan view thereof; and,

FIG. 6 is a bottom plan view thereof.

The broken line showing of environment in FIGS. 1, 3 and 6 is for illustrative purposes only and forms no part of the claimed design.
